UNITED STATES PATENT OFFICE

2,619,060

THREAD CUTTER FOR SHOE SEWING MACHINES

Alfred S. Clark, Beverly, Mass., assignor to United Shoe Machinery Corporation, Flemington, N. J., a corporation of New Jersey.

Original application November 16, 1948, Serial No. 60,209. Divided and this application November 23, 1949, Serial No. 129,033.

5 Claims. (Cl. 112—252)

1.

The present invention relates to McKay shoe sole sewing machines and more particularly to improvements in thread severing devices for a straight hook needle machine having a rotary shoe supporting horn in which the stitch forming devices, except for a needle threading whirl, are located above the horn at the opposite side of the work from the horn. An example of a machine of this type is disclosed in United States Letters Patent No. 710,612, granted October 7, 1902 upon application of E. P. Richardson, No. 1,114,287, granted October 20, 1914 upon application of E. J. Ray and No. 1,738,778, granted December 10, 1929 upon application of B. T. Leveque. The illustrated machine is the same as that more fully described in an application for United States Letters Patent Ser. No. 60,209, filed November 16, 1948, of which the present application is a division.

An object of the invention is to provide a novel and improved form of thread cutter for a machine of the type referred to, which is of simple and compact construction and will operate with reliability and with greater effective cooperation with the other actuating devices of the machine than with machines of prior construction.

One difficulty in providing a machine having a rotary shoe supporting horn, with a thread cutter arises from the crowded relationship of the stitch forming and work feeding devices of the machine at the upper side of the work opposite the horn. Because of the crowded relationship of these devices in prior machines and particularly because a presser foot is mounted above the work directly in the seam line behind the needle, according to the usual practice, it is necessary to provide a retractable thread cutter which is movable out of the range of action in these devices to a position where it will not interfere with their operation or with the presentation of the shoe by the operator to the operating point in the machine. When arranged for movement out of the range of the operating devices, it is necessary to locate the thread cutter accurately when moved into operative position so that reliable severance of the thread will be accomplished.

In accordance with the object of the invention a retractable thread cutter is provided, connected in spaced relation with a guide member actually engaging the needle to position the thread cutter accurately relatively to the needle loop while

severing the thread and to disengage the needle for normal operation of the machine when moved out of the range of the stitch forming devices. Such arrangement is rendered possible by the use of a presser device disposed out of line with the seam at the rear of the needle where it does not interfere with the movements of the guide member. Preferably, the guide member is forked to engage the needle while the thread is being severed and in one form of this feature the guide member is mounted within a slot in a block which also carries the knife for the thread cutter. The use of a slotted mounting block is of advantage also in supporting a guard for the cutting edge of the knife acting to protect the work operated upon from contact with the knife while the thread is being severed.

These and other features of the invention consist in the constructions, combinations and arrangements of parts hereinafter described and claimed, the advantages of which will readily be apparent from the following description taken in connection with the accompanying drawings, in which:

25 Fig. 1 is a view in front elevation of a sewing head and a portion of a rotary work supporting horn in a machine embodying a thread cutter having the features of the present invention;

Fig. 2 is a perspective detail view of the straight hook needle in the machine of Fig. 1, the upper end of the work supporting horn and the thread cutter in inoperative position, illustrating the relationship of the parts;

Fig. 3 is a similar view showing the thread cutter in operative position; and

Fig. 4 is a perspective detail view of a modified form of thread cutter in operative position.

The machine illustrated in the drawings is of the same construction and mode of operation, except as hereinafter pointed out, as that disclosed in the Richardson and Ray patents above referred to. Referring to Fig. 1 of the drawings, the straight hook needle is indicated at 2, the rotary shoe supporting horn at 4 and the feed

45 point at 6. Other stitch forming devices including a cast-off 7 also are provided acting during sewing to draw loops of thread upwardly through the work and to set each stitch by tightening the loops against the work. Instead of locating the work clamping member along the line of the seam

in advance of the feed point according to common practice, a shoe sole 8, presented to the illustrated machine is engaged along its upper surface by a clamping member in the form of a roll 10 close behind the needle at the rear side of the seam line opposite a circular shoe supporting portion 12 of the horn. The presser roll is rotatable on a shoulder screw 14 threaded into a bracket 16 secured to the lower end of a presser foot bar 18, in turn slidably mounted in the frame of the machine for clamping movement toward and from the work. The bracket 16 is formed with a laterally projecting slotted arm through which a clamping stud 20 is inserted to secure the bracket to the presser bar, all the presser roll supporting parts being disposed behind the needle and the seam line.

As has been stated, the arrangement of the presser roll 10 behind the seam line opposite the needle path and the elimination of the customary presser foot enables the use of the improved form of thread cutter. The thread cutter of the present invention is retractable from operating position, is manually actuated along the seam line and is guided accurately with relation to one side of a loop 22 of thread retained on the needle above the work after formation of the last stitch in a seam to permit reliable severing of the thread. By this arrangement the thread is severed close to each last formed stitch 24 while leaving sufficient thread between the needle and the horn to insure proper formation of the first stitch in the new seam.

The thread cutter comprises a knife 26 mounted to swing toward and from the needle path and to enter between the sides of the final loop of thread 22 on the needle at the end of a seam. The thread cutter knife is a flat blade, pointed at its cutting end with its forwardly facing edge at the point sharpened while the rearward edge remains unsharpened to avoid severing both sides of the needle loop. The knife is secured in a slot of a block 28 fastened to the lower end of a reversely bent actuating lever 30 guided to move along the seam line. The lever extends upwardly from the block 28 to a right angle bend, thence horizontally to a fulcrum stud 32 and then upwardly to a handle portion. The stud 32 projects from a plate 33 clamped to the presser foot supporting bar 18 and acts to guide the lever 30. The handle portion of the lever 30 also carries a stop clip 34 adjustably secured by a screw 36 passing through a slot in the clip, so arranged that the clip will engage the presser foot bar to limit the thread cutting movement of the knife 26 and prevent it from engagement with the other operating parts of the machine. The lever 30 is normally held in an inoperative position with the knife retracted out of the needle path by a tension spring 38 connected between a pin on the lever 30 and a pin of the machine frame.

To guide the movements of the knife 26 and to insure accurate entry between the sides of the loop 22 of thread carried by the needle, a second slot in the block 28 above the knife 26 supports a forked guide member 40 in parallel relation to the blade of the knife. The fork in the guide member provides an opening of sufficient width to fit the diameter of the needle so that when it engages the needle the point of the knife is positioned without fail between the sides of the needle loop. The width of the guide member is such that it moves readily past the presser roll 10 and its bracket 16.

To prevent damage to a shoe bottom by en-

gagement with the knife 26 the cutting edge of the knife is surrounded by the arms of a guard plate 42 mounted in the lower slot of the block 28. The guard plate 42 has one arm curved beneath and upwardly over the cutting edge of the knife from a location between the knife and the point on the shoe bottom operated on by the needle and another arm bent into a horizontal position to extend behind the needle loop and beyond the point of the knife to prevent accidental contact by the hands of the operator or by the work with the knife point.

In another form of the knife a guard plate is found unnecessary inasmuch as the forward edge of the knife is left unsharpened, the rearward edge only being employed to sever the thread. Such knife is indicated at 44 in Fig. 4 and is mounted in the same manner as in the previous arrangement within the lower slot of the block 28. The same guide member 40 also is employed with the unguarded knife 44. In this instance, however, the knife is so shaped that during its cutting stroke the rearward edge of the knife does not move rearwardly beyond the central axis of the needle, the knife cutting the forward side of the loop without entering between the two sides. Also the use of a sharpened point on the knife is eliminated so that no guard is required in this instance for the point.

The nature and scope of the invention having been indicated and a particular embodiment having been described, what is claimed is:

1. A shoe sewing machine having a straight hook needle and other stitch forming devices acting during sewing to draw loops of thread through the work and to tighten the loops against the work, and a thread cutter comprising a knife arranged to sever the thread in a loop withdrawn from the work by the needle, in combination with a guide member operatively connected to and in spaced relation above the knife for positioning the thread cutter relatively to the needle loop by engagement with the needle while the knife is being actuated to sever the thread.

2. A shoe sewing machine having a straight hook needle and other stitch forming devices acting during sewing to draw loops of thread through the work and to tighten the loops against the work, and a thread cutter comprising a knife arranged to sever the thread in a loop withdrawn from the work by the needle, in combination with a forked guide member connected to the knife with its fork in parallel relation to and above the knife for engaging the needle within its fork to position the thread cutter relatively to the needle loop while the thread is being severed.

3. A shoe sewing machine having a straight hook needle and other stitch forming devices acting during sewing to draw loops of thread through the work and to tighten the loops against the work, and a thread cutter comprising a knife arranged to sever the thread in a loop withdrawn from the work by the needle, in combination with a guide member for positioning the thread cutter relatively to the needle loop arranged to surround the needle while the thread is being severed, and a block having spaced parallel slots one above the other within which the thread cutter knife and the guide member are mounted.

4. A shoe sewing machine having a straight hook needle and other stitch forming devices acting during sewing to draw loops of thread through the work and to tighten the loops against the work, and a thread cutter comprising a knife arranged to sever the thread in a loop withdrawn

from the work by the needle, in combination with a guide member connected in spaced relation to the knife for positioning the thread cutter relatively to the needle loop and arranged to surround and engage the needle while the thread is being severed, and a guard mounted with the knife to project between the cutting edge of the knife and the point on the work operated upon by the needle and in front of the cutting edge of the knife.

5. A shoe sewing machine having a straight hook needle and other stitch forming devices acting during sewing to draw loops of thread through the work and to tighten the loops against the work, a work support, a work clamping mem- 15

ber at one side of the seam line and a thread cutter comprising a knife arranged to sever the thread in a loop withdrawn from the work by the needle, in combination with a guide member connected in spaced relation to the knife for positioning the thread cutter relatively to the needle loop and arranged to surround the needle while the thread is being severed and an actuating lever to which the knife and guide member are secured, 10 guided to move along the seam line past the work clamping member in severing the thread.
